United States Patent Office.

BENJAMIN S. LAWSON, OF NEW YORK, ASSIGNOR TO AUGUSTUS M. MILLER, OF BROOKLYN, NEW YORK, AND ALFRED GILL, OF ORANGE, NEW JERSEY.

Letters Patent No. 94,420, dated August 31, 1869.

IMPROVED SASH-HOLDER.

The Schedule referred to in these Letters Patent and making part of the same.

To all whom it may concern:

Be it known that I, BENJAMIN S. LAWSON, of New York, in the county of New York, and State of New York, have invented a new and valuable Improvement in Sash-Fasteners; and do hereby declare that the following is a full, clear, and exact description of the construction and operation of the same, reference being had to the annexed drawings, making a part of this specification, and to the letters and figures of reference marked thereon.

Figure 1, of the drawings, is a perspective view of my invention.

Figure 2 is a cross-section of same.

Figure 3 is a perspective view of sash with fastener.

Figure 4 is a side view, with side plate removed, and sash-mouldings in section.

My invention relates to means for holding and operating window-sash; and

It consists mainly in a novel arrangement of devices intended to serve an efficient purpose in the use named.

The letter A, of the drawings, represents a section of a window-jamb, and

The letter B, a section of a window-sash, with my device arranged therein.

The letter C represents a metallic plate, attached to the side of the sash by screws, adjoining which I form a slot in the face of the sash, as shown, to provide for the adjustment of the elastic wedge a and the roller c, as hereinafter mentioned.

The letter a represents a wedge of India rubber, or

other elastic substance, arranged in the bottom of the slot, as shown, and

The letter c represents a roller, playing loosely in said slot, and arranged to move back and forth therein.

My device operates as follows:

When the sash is in place, the roller c presses against the rear side of the window-moulding, and as the thin edge of the wedge is placed downward, it allows the window to be raised with ease. When, however, the sash is raised to the desired altitude, the weight of the same falls upon the roller, pressing it against the partial shoulder formed by the increasing thickness of the wedge upward, and thereby holding said sash in place.

I usually arrange a roller, c, on each side of the window-sash.

The above and foregoing description is made applicable to all kinds of sliding frames, and is especially adapted to the windows of carriages and railway-cars.

What I claim as my invention, and desire to secure by Letters Patent, is—

The window-sash adjuster herein described, having elastic wedge a and roller c, arranged in a slot, as described, substantially as specified.

In testimony that I claim the above, I have hereunto subscribed my name, in the presence of two witnesses.

BENJ. S. LAWSON.
